UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 908,655.

Specification of Letters Patent.

Patented Jan. 5, 1909.

Application filed November 8, 1908. Serial No. 342,535.

To all whom it may concern:

Be it known that I, JACOB FELBEL, citizen of the United States, and resident of the Borough of Manhattan, city of New York, in the county of New York and State of New York, have invented certain new and useful Improvements in Type-Writing Machines, of which the following is a specification.

My invention relates more particularly to 10 the ribbon mechanism of that class of type-writing machines employing a vibratory ribbon carrier or ribbon vibrator which normally maintains the ribbon away from the printing point and is automatically moved 15 or caused to be thrown to bring the ribbon opposite the printing point when the printing keys are operated.

The main object of my invention is to provide means for varying the throw of the ribbon vibrator so as to bring different width-wise portions or fields of the ribbon opposite the printing point on the platen at will.

My invention may be employed to especial advantage with ribbons which are divided 25 into longitudinal fields having different characteristics or colors, but said invention may also be used with ribbons of uniform character throughout in order to more thoroughly exhaust the ink from such ribbons.

To the above and other ends my invention 30 consists in the features of construction, combinations of devices and arrangements of parts hereinafter described and particularly pointed out in the claims.

I have shown my invention as applied to a 35 Monarch typewriter wherein there is employed an operating lever that is connected at one arm with the ribbon vibrator and at the other arm through an actuating link with 40 a key-actuated universal bar and lever.

In carrying out my invention I fulcrum the operating lever in a vertically movable fulcrum block or member, the vertical position of said block being controlled by a 45 rotary device or cam member which is adjustable at will from the front of the machine, though it may be operated as well from the side of the machine or from any other point convenient for the user. The rotary device 50 or cam member also guides and controls the actuating link which is adapted to be connected with the operating lever at one or another of a plurality of points disposed longitudinally of said link.

By means of the devices just briefly described I am enabled to control and vary the normal position of the operating lever, ribbon vibrator and the ribbon without changing the normal positions of the devices for actuating them, with the result that while the throw or amount of movement of the ribbon vibrator is always the same, yet the points at which said movement begins and ends may be altered so that different width-wise portions of the ribbon may be presented to the types.

While I have shown one form of my invention as embodied in a Monarch machine it is to be understood that the various features of said invention in whole or in part may be adapted to other forms of writing machines.

In the accompanying drawings, Figure 1 is a vertical longitudinal sectional view of a typewriting machine embodying my invention, parts of the machine being omitted and parts broken away. Fig. 2 is a fragmentary sectional view corresponding with Fig. 1 but showing various parts of the ribbon mechanism in different relations from those in which they appear in said Fig. 1. Fig. 3 is a transverse vertical sectional view of the machine taken on a plane forward of the top plate, parts of the machine being omitted and parts broken away. Fig. 4 is an enlarged perspective view with parts in section, the view showing parts of the ribbon mechanism in the same relations in which they appear in Fig. 1. Fig. 5 is an enlarged detail sectional view of a part hereinafter termed a fulcrum member or fulcrum block, said figure also showing the mounting of said block and a part of the operating lever for the vibrator.

In the drawings, the base 1 of the machine is surmounted by corner posts 2 which in turn sustain a top plate 3. A front plate 4 extends across the front of the machine and is secured to the front corner posts by screws. 5. Key levers 6 are fulcrumed on a fulcrum plate 7 in the rear of the base and each key lever is provided with a restoring spring 8. A sub-lever 9 is pivoted at 10 to each key lever, said sub-lever being slotted at its lower end portion to coöperate with a fixed abutment 11 and being connected at its upper end by a link 12 with a type bar 13, said type bar being pivotally mounted in a hanger 14 secured by a screw 15 to a seg-

mental type bar support 16. The type bar hangers are mounted in segmental series at the front of the segment 16 and the type ends of said type bars are supported on a 5 segmental type rest 17. The type bars are adapted to coöperate with the front face of a rotary platen 18 mounted in a platen carriage comprising side bars 19 and a rear bar 20. The top and bottom faces of the rear 10 bar are formed with grooves to receive anti-friction balls 21, said balls also coöperating with grooved guide rails 22 fixed to standards 23 rising from the top plate. A carriage feed rack 24 is mounted on the carriage 15 and normally meshes with a feed pinion 25 operatively connected with a toothed escapement wheel 26. Coöperative with the escapement wheel are escapement dogs 27 mounted at the top of a vibratory dog carrier or rocker 28, said rocker having a horizontally disposed arm 29 which is connected by a link 30 with an arm or lever 31 projecting rearwardly from about the middle of a rock shaft 32 pivoted on screw pivots 25 33 secured in the sides of the base. The rock shaft 32 and arm 31 are part of a universal bar frame which comprises in addition side arms 34 and a universal bar proper 35 extending from side to side of the machine 30 beneath the series of key levers and joining the side arms 34 and the central arm 31. The universal bar frame is provided with the usual restoring spring (not shown). The carriage is provided with a downwardly 35 extending lug or pin 36 which is connected by a band or strap 37 with a spring drum 38 which tends constantly to draw the carriage leftward over the top plate. When the printing keys are actuated the escapement 40 devices cooperate in a known manner to permit the carriage to move leftward or in letter space feed direction a letter space distance at a time.

Ribbon spools 39 are mounted above the 45 top plate one at each side of the machine and forwardly of the platen, said ribbon spools receiving a ribbon 40 which, in the present instance, is shown as divided into two longitudinal fields or stripes *a* and *b* of different 50 characteristics; that is to say, the field *a* may be of one color such as black and the field *b* of a different color, such as red, for example, or the field *a* may be impregnated with copying ink and the field *b* with record ink. The 55 ribbon may be caused to wind back and forth from one spool to the other by any suitable ribbon feeding mechanism, that shown in the drawings being the usual mechanism of the Monarch machine. Each ribbon 60 spool is operatively connected with a small beveled gear 41 which meshes with a beveled pinion 42 fixed to the front of a horizontal shaft 43, at the rear of which is a beveled pinion 44 meshing with a beveled 65 driving pinion 45 fixed to a horizontal driv-

ing shaft 46, said driving shaft extending from side to side of the machine near the rear thereof and carrying one of the driving pinions 45 near each end. The driving shaft is operatively connected with and receives motion from the spring drum 38 during the travel of the carriage in a letter space feed direction, the connections comprising beveled gears 47 and 48, the former operatively connected with the spring drum by the usual 70 pawl and ratchet (not shown) and the latter mounted on the driving shaft and connected to the latter by the usual pin and slot connection so that while the pinion 48 and the driving shaft always turn together, said 75 driving shaft may be moved endwise without affecting said gear 48. The back and forth endwise movements of the shaft 46 serve to connect one or another of the driving pinions 45 with its associate pinion 44 80 and thereby to turn one or the other of the ribbon spools 39 to wind the ribbon 40 thereon. That portion of the ribbon which extends between the spools passes through and is guided by a vibratory ribbon carrier or 85 ribbon vibrator 49 which is supported and guided on the upright arms 50 of a guide bracket 51, said guide bracket being secured to the top plate by screws 52. The lower end portion of the vibrator is bifurcated and 90 the arms 53 of the bifurcated portion are curled or bent to receive and hold a cross pin 54 which works in the slotted forward end of an operating lever 55, the coöperation being 95 such that the vibrator and its operating 100 lever may always be moved freely relatively to each other. In the present instance the operating lever, instead of having a fixed fulcrum as is usual in the Monarch machine, is fulcrumed on a fulcrum pin 56 which is 105 carried by a fulcrum block, plunger or slide 57, the latter, as best shown in Fig. 5, being cylindrical in form and being formed with a kerf or slot 57^a in which the operating lever 110 is received. The fulcrum block is provided with an enlargement or head 58 which is received in an opening or depression 59 in a guide member 60, said guide member resembling a socket or a hollow screw. The 115 guide member is formed with an opening 120 which receives the body portion of the fulcrum block 57 and in which the latter is 125 slidably, said guide opening being of lesser diameter than the depression 59 and connected with the bottom of said depression, 130 thereby forming an annular shelf or flange 61 against which the under side of the head 58 of the fulcrum block normally rests, as shown in Fig. 5.

The lower portion of the guide member 60 125 is provided with a slot or kerf 62, for a purpose presently to be explained, and the exterior of said member is threaded to co-operate with a threaded opening in the top plate 3, said member being preferably 130

screwed down into said opening until a flange 63 at the top of the member contacts with the upper surface of the top plate. The flange 63 is formed with nicks or slots 64 to receive a screw-driver or other tool by which the guide member may be readily turned for adjustment or removal. At either side of the slot 62, the bottom portion of the member 60 is provided with cut-ways or notches 65, said notches being oppositely disposed and being adapted to receive the projecting portions of the fulcrum pin 56 when the fulcrum block or plunger 57 is raised in the guide member 60, in a manner presently to be described. The shorter rear arm 66 of the operating lever 55 has its top face 67 preferably flat. As best shown in Fig. 5, the face 67 normally contacts with the closed end of the slot 57^a at the rear thereof so that bodily longitudinal movement communicated to the fulcrum block will also be communicated to the operating lever without affecting the normal relation of the latter and the fulcrum block. Forward of its fulcrum the operating lever is inclined downwardly so that it will not be in contact with the forward part of the closed end of the slot 57^a during vibratory movements of the operating lever. The arrangement is such that the fulcrum block serves as a stop for the rear arm of the operating lever but not for the forward arm. It does not act as a stop for the forward end of the lever in order that there may be no sudden arrest of and shock to the finger in the upward or printing movement of the lever. If desired, however, the lever may be stopped in its upward throw. I prefer, though, if any such stop be used that it be an adjustable one whereby the throw of the ribbon may be nicely regulated. Such a stop is shown in connection with Fig. 5 and consists of a lip 67^b extending laterally from the shorter arm of the operating lever and a screw 67^b arranged in an arm 67^c formed on or attached to one fork of the bifurcated end of the fulcrum block 57.

In operation, when the operating lever is pulled down the lip strikes the point of the screw and limits the upward throw of the lever and the ribbon. These devices are operable in both positions of the fulcrum block and the stop screw 67 may be adjusted to regulate the extent of the throw. Thus it will be seen that the upward movements of the ribbon vibrator and its operating lever may be limited for each field of the ribbon so that there may be no overthrow of the ribbon, thus insuring the striking of the types on that field only which may be adjusted for use. With a positive stop such as just described it is desirable to employ a yielding connection somewhere between the finger key and the stop, an example of which may be seen in my prior patent No. 674,312, dated

May 14th, 1901. Adapted to engage with the top face 67 are two laterally projecting actuating devices or lugs 68 and 69 formed one above the other at the upper end portion of an actuating link 70, which link is pivotally connected at 71 with the central arm 31 of the universal bar or lever frame. The body of the link 70 is preferably round in cross section but the upper portion from which the lugs 68 and 69 extend is preferably square in cross section and is adapted to be reciprocated in a guide opening or slot 72 formed in the horizontal portion 73 of an angular guide bracket 74, depending from the underside of the top plate and suitably secured thereagainst.

The fulcrum block or plunger 57 is adapted to be raised or lowered in the guide member 60 to vary the normal position of the operating lever 55 and ribbon vibrator 49, and the link 70 is adapted to be switched or shifted to enable either of the engaging or actuating devices 68 and 69 to coöperate with the rear arm of the operating lever, the lug 68 engaging with the lever when the latter is normally in its lowermost position and the lug 69 engaging with said lever when the latter is in its uppermost position. The preferred means for shifting the operating lever 55 and switching the link 70 will now be described in detail. Arranged below the fulcrum block 57 is a rock shaft 75, said rock shaft being journaled in arms or lugs 76 (Fig. 3) depending from the under side of the top plate, one near the right-hand side of the machine and one near the middle thereof. Arms or cam pieces 77 are provided with collar portions 78 through which the rock shaft 75 passes, said arms 77 being secured in fixed relation with the rock shaft by pins or rivets 79 passing through the collar portions 78 into the rock shaft. The upper portions of the arms 77 are provided with cam slots 80, each cam slot having a dwell 81 at the rear end and a dwell 81^a at the front end, each cam slot and its dwells providing a continuous opening which receives one of the projecting end portions of the fulcrum pin 56. Of course other projections or lugs on the fulcrum block, but not connected with the fulcrum pin, might be employed to engage the cam slots if preferred. Arranged between the arms 77 is a curved cam plate 82, said cam plate being provided with ears or tabs 83 which are suitably secured to the inner walls 120 of the arms 77, as by rivets 84. The curved cam plate 82 is provided with angularly disposed cam slots 85 and 86 which are joined by a dwell 87, forming a continuous opening which is adapted to receive the upper portion 125 of the link 70 below the rear arm 66 of the operating lever.

It will be understood from what has been said and from an inspection of Fig. 4 that the arms or cam pieces 77 and the cam plate 82 130

constitute a rotary cam member and support which guides and supports the fulcrum block 65 and the operating lever 55 and also guides the link 70. The rotary member, comprising the arms 77 and plate 82, is adapted to turn with the rock shaft 75 about the axis of said rock shaft as a center, in order to raise and lower the operating lever 55 and vary its relation with the actuating link 70. The devices for controlling the position of the rotary member comprise a crank arm 88 having a collar portion 89, which is secured by a pin 90 to the rock shaft 75 at the right of the right-hand cam piece or arm 77. The crank arm 88 is pivotally connected at 91 with a push bar or rod 92, the front end portion of which passes through and bears in an opening in the front plate 4, the end of said rod being provided with a finger button 93. A spring 95, to the back of the front plate 4 and co-operates with notches or depressions 96 and 97 to maintain the push bar 92 and through it the rotary member and the parts controlled thereby in adjusted positions.

Referring now to the operation of the mechanism and assuming that the parts are normally related as illustrated in Figs. 1 and 4, it will be understood that when the universal bar frame is depressed by the printing keys, it will draw the link 70 longitudinally downward, causing the engaging device or lug 68 to pull down the rear arm 66 of the operating lever and to swing the forward arm of said lever upward, the latter carrying with it the ribbon vibrator 49. The parts are so proportioned that this upward movement of the vibrator will bring the upper field *a* of the ribbon opposite the printing point. It will be understood that during this actuation of the operating lever the latter will turn on the fulcrum pin 56 as on an axle, said fulcrum pin remaining motionless, seated in the dwells 81 in the arms 77 and contacting with the rear closed ends of said dwells. When pressure on a finger key is removed the parts are restored to normal position by gravity and the usual restoring spring on the universal bar; but if desired the operating lever may have a separate returning spring. As will be apparent, with the parts normally related as in Fig. 1, the throw or upward movement of the vibrator will always be the same in extent and will always start from the same point, so that the ribbon will always be raised to the same height and the type impressions will follow in a path along the upper field or portion of the ribbon and longitudinally thereof.

When it is desired to make use of the lower field *b* of the ribbon, the button 93 is pushed rearwardly by the operator, causing the notch 86 to disengage from the detent 94 and the notch 97 to engage said detent. The

rearward movement thus communicated to the push bar 92 is equal to the distance between the notches 96 and 97 and suffices to swing the crank arm 88 from the position shown in Figs. 1 and 4 to that shown in Fig. 2. The turning of the crank arm turns the rock shaft 75 and through it the rotary device comprising the arm 77 and the cam plate 82; this movement swinging said rotary device rearwardly to the position shown in Fig. 2. During the first part of the rearward swinging movement of the rotary cam device, the cam 85 will act on the link 70 to swing the upper end portion thereof leftward laterally or transversely of the operating lever, the connection 71 between the lower end of the link and the universal bar frame being sufficiently loose to permit of this swinging movement of the upper end portion of said link. During this swinging movement of the link it is guided in the slot 72 in the bracket 74. When the forward end of the cam slot 85 reaches the link and the latter is at the rear end of the dwell 87, said link will have been swung far enough to the left of the operating lever to disengage the lug 68 entirely from said lever. During this movement of the upper end portion of the link 70, the dwells 81 in the arms or cam pieces co-operate with the end portions of the fulcrum pin 56; and as said dwells are struck on arcs the centers whereof are coincident with the axis of the rock shaft 75, the fulcrum pin will continue to remain at the same distance from said axis and consequently neither the fulcrum block 57 nor the operating lever 55 will be affected. The parts are so proportioned that the front ends of the dwells 81 will not reach the fulcrum pin 56 until after the lug 68 on the link 70 has been swung out of the path of the rear arm of the operating lever. The cam slots 80 are inclined so that their forward ends where they join the dwells 81^a are further from the axis of rotation than are their rear ends where they join the dwells 81. Consequently the cams 80 next begin to act on the fulcrum pin 56 and will cam the latter away from the axis of rotation of the shaft 75, lifting the fulcrum block 57 upwardly in the bearing member 60, said fulcrum block carrying with it the operating lever and the ribbon vibrator.

During the operation of the cam slots 80 on the fulcrum pin 56 the dwell 87 in the cam plate 82 will be in co-operation with the link 70, so that the latter will remain unaffected. When the ends of the fulcrum pin 56, however, enter the dwells 81^a which are struck from the axis of the rock shaft 75 as a center, the rear end of the cam slot 86 will be ready to co-operate with the link 70 and by the time the closed forward ends of the dwells 81^a engage with the fulcrum pin the link 70 will have been cammed or swung by the cam

slot 86 rightwardly back towards the operating lever. After the disengagement, however, of the actuating device or lug 68 on the link 70 from the operating lever, and prior to 5 the subsequent engagement of the link 70 with said lever, the cams 80 will have acted in the manner described to lift the operating lever so that the latter will enter the kerf or slot 62 and the fulcrum pin 56 will enter the 10 slots or cut-aways 65, and said operating lever will be in the position shown in Fig. 2. Consequently, when the link 70 is cammed by the cam slot 86 back to normal position the rear arm of the operating lever will be 15 above the lug 68 on the link 70 and will be engaged by the upper lug or engaging device 69 on said link. The various parts will now normally be in positions illustrated in Fig. 2, and it will be understood that the ribbon 20 vibrator and the working portion of the ribbon will have been moved upward to an extent corresponding with the upward shifting movement of the operating lever and its fulcrum. If, now the printing keys be operated 25 the ribbon will be moved upward in the same manner as before and to the same extent, but the normal position or the point at which the upward movement begins having been altered the upper limit of movement of 30 said ribbon or the point at which its upward movement ceases will have been correspondingly altered. The arrangement is such that at this time the lower field *b* of the ribbon will be presented to the types and since the 35 throw or extent of movement is always the same the types will follow in a path along the lower field *b* and longitudinally thereof.

Whenever it is desired to again make use of the upper ribbon field or stripe *a*, the button 93 is pulled outward until the bar or rod 92 and the parts controlled thereby have been moved from the positions illustrated in Fig. 2 to those illustrated in Figs. 1 and 4. Subsequent operations of the printing keys 45 will serve to bring the upper field *a* of the ribbon opposite the printing point in the manner hereinbefore described.

Various changes may be made within my invention.

50 What I claim as new and desire to secure by Letters Patent, is:—

1. In a ribbon mechanism, the combination of a ribbon operating lever, means for shifting said lever so that it may occupy at 55 will normally either one of two positions, key controlled devices for operating said lever each adapted to engage said lever at substantially the same distance from its fulcrum and one being out of use when the 60 other is in use, and means for automatically disengaging the operative one of said devices when the lever is shifted so as to enable the other one of said devices to be brought into coöperation with said lever.

65 2. In a ribbon mechanism, the combina-

tion of a ribbon operating lever having a shifting fulcrum to change the ribbon field, and a pair of devices for said lever adapted for alternate action at will and both operative upon said lever at substantially the 70 same distance from its fulcrum.

3. In a ribbon mechanism, the combination of a ribbon operating device shiftable at will to either one of two normal positions to change the ribbon field, and a pair of 75 shiftable devices, one adapted to the operating device in one of its positions and the other to the operating device in the other of its positions.

4. In a ribbon mechanism, the combination of a ribbon operating lever shiftable bodily so as to occupy normally either one of two working positions, and a pair of devices shiftable simultaneously with said lever, one of said devices being adapted to 85 co-act with said lever in one only of its normal positions and the other device being adapted to co-act with said lever only in the other of its normal positions, both of said devices being arranged to co-act with said 90 lever at substantially the same distance from the fulcrum of said lever.

5. In a ribbon mechanism, the combination of a shiftable operating lever adapted to be set alternately in either one of two normal positions to change the ribbon field, and an actuating link shiftable with said lever and provided with two actuating devices engageable alternately with said lever at substantially the same distance from its fulcrum. 100

6. In a ribbon mechanism, the combination of a ribbon operating lever, an actuating link therefor having two engaging fingers, a cam for shifting the lever from one normal position to another to change the ribbon 105 field, and a cam for shifting the actuating link and bringing into coöperation with said lever one or the other of said fingers according to the shift of said lever.

7. In a ribbon mechanism, the combination of an operating lever shiftable so as to occupy normally either one of two positions to change the ribbon field, a second lever, an actuating link connecting said levers, said link being shiftable and provided with two 110 alternately operative lever actuating devices, one only of said devices coöperating with said lever in each of its two said positions.

8. In a ribbon mechanism, two operating 115 levers relatively shiftable to vary the normal position of the ribbon, said levers being normally connected together and to the ribbon and the distance between the connecting points being altered when the relative 120 shifting movement takes place.

9. In a ribbon mechanism, the combination of a shiftable ribbon operating lever, a universal bar, a lever connected with said universal bar, and a link interposed between 125

said levers and provided at one of said levers with alternately engaging lever actuating devices.

10. In a ribbon mechanism, the combination of a shiftable ribbon operating lever adapted to occupy at will either one of two normal working positions and having a substantially uniform throw in each such working position, and a stop shiftable with said lever to positively arrest said lever at the end of its movement to carry the ribbon to the printing point; said stop being equally operative in both normal positions of said lever.

15. 11. In a ribbon mechanism for typewriting machines, the combination of a vibrator, an operating lever, a vertically slideable fulcrum device carrying said lever, fixed means for guiding said slideable fulcrum device, and 20 means wholly independent of the guiding device for supporting and shifting said fulcrum device.

25. 12. In a ribbon mechanism for typewriting machines, the combination of a vibrator, an operating lever, a fulcrum block carrying said lever, and means for supporting and shifting said fulcrum block, said fulcrum block also serving as a stop for said operating lever.

30. 13. In a ribbon mechanism for typewriting machines, the combination of a vibrator, an operating lever therefor, a slideable fulcrum block on which said operating lever is pivoted, a stationary guide in which said fulcrum block is inclosed, and means for 35 moving said fulcrum block in its guide.

14. 14. In a ribbon mechanism for typewriting machines, the combination of a vibrator, an operating lever therefor, a slideable fulcrum block on which said operating lever is pivoted, an adjustable hollow screw inclosing said fulcrum block and serving as a guide therefor, and means for moving said fulcrum block within said hollow screw.

45. 15. In a ribbon mechanism for front strike typewriting machines, the combination of a vibrator, an operating lever pivotally connected therewith, a fulcrum block carrying said lever, a hollow screw supported on the top plate and adjustable thereon, said 50 screw inclosing said fulcrum block and serving as a guide therefor, and hand operated means for sliding said fulcrum block up and down in said hollow screw.

55. 16. In a ribbon mechanism for typewriting machines, the combination of a ribbon vibrator, an operating lever therefor, a fulcrum block, and a device for supporting and shifting the fulcrum block, said device comprising a member having cam slots engaging 60 the fulcrum block.

17. 17. In a ribbon mechanism for typewriting machines, the combination of a ribbon vibrator, an operating lever therefor, a fulcrum block, a device for supporting and 65 shifting the fulcrum block, said device com-

prising pivoted cam plates, and hand operated means for turning said device to shift said fulcrum block and operating lever.

18. In a ribbon mechanism for typewriting machines, the combination of a ribbon vibrator, an operating lever therefor, a slideable fulcrum block on which said lever is mounted, said fulcrum block having oppositely disposed projections, and a device for supporting and shifting said fulcrum block, said 75 device comprising a member having cam slots engaging the projections of said fulcrum block.

19. In a ribbon mechanism for typewriting machines, the combination of a ribbon vibrator, an operating lever therefor, a slideable fulcrum block on which said lever is mounted, said fulcrum block having oppositely disposed projections, a device comprising pivoted cam plates which engage the projections on said fulcrum block, and hand operated means for turning said device to shift the fulcrum block and change the normal positions of the operating lever and the vibrator.

20. In a ribbon mechanism for typewriting machines, the combination of a ribbon vibrator, an operating lever therefor, a device for supporting and shifting the fulcrum of said operating lever, said device comprising pivoted cam plates, and hand operated 95 means for turning said cam plates to shift the operating lever, said hand operated means comprising a crank arm and a key operated bar pivotally connected therewith.

21. In a ribbon mechanism for typewriting 100 machines, the combination of a ribbon vibrator, an operating lever therefor, and a device for supporting and shifting the fulcrum of said operating lever, said device comprising slotted plates, and a rock shaft to which 105 said plates are fixed.

22. In a ribbon mechanism for typewriting machines, the combination of a ribbon vibrator, an operating lever therefor, a device for supporting and shifting the fulcrum of said operating lever, said device comprising slotted plates, and a rock shaft to which 110 said cam plates are fixed, and hand operated means for turning said rock shaft to shift the normal position of said operating lever, said 115 means comprising a crank arm and a key operated bar pivotally connected therewith and operative from the front of the machine.

23. In a ribbon mechanism, operating means comprising a universal bar, and a link 120 and a lever normally engaging each other and operable from said universal bar, said link being constructed and operative to engage with said lever at will at different points in the length of said link.

24. In a ribbon mechanism for typewriting machines, the combination of a ribbon vibrator, and operating means therefor comprising a link and a lever normally engaging each other, said link being provided with a 130

plurality of engaging devices arranged at different points in its length and being operative to engage at will with said operating lever at any one of said different points.

- 5 25. In a ribbon mechanism for typewriting machines, the combination of a ribbon vibrator, operating means therefor comprising an operating lever pivotally connected with the vibrator, and a link normally engaging with said lever, a key actuated universal bar with which said link is pivotally connected, and means for shifting said link and said lever and causing said link to engage said lever at different distances from the connecting point between said link and said universal bar.
- 20 26. In a ribbon mechanism for typewriting machines, the combination of a ribbon vibrator, operating means therefor comprising a link and a lever normally engaging each other, said link being provided with a plurality of engaging devices arranged at different points in its length, a key actuated universal bar with which said link is pivotally connected, and means for shifting said link and said lever at will and causing one of said en-

gaging devices on said link to be disengaged from said lever and another one to be engaged therewith.

27. In a ribbon mechanism for typewriting 30 machines, the combination of a ribbon vibrator, an operating lever therefor, a link provided with a plurality of engaging devices arranged at different points in its length, and a device for supporting and shifting the fulcrum of said operating lever and for shifting said link to cause one of its engaging devices to be disengaged from said operating lever and another to be engaged therewith, said device comprising pivoted cam plates by 35 40 which the operating lever is supported and shifted and also comprising a cam plate by which said link is shifted.

Signed at the borough of Manhattan, city of New York, in the county of New York, 45 and State of New York, this 7th day of November A. D. 1906.

JACOB FELBEL.
